C. Snowdon.

UNITED STATES PATENT OFFICE.

EDWIN CRALL, OF ALMA CENTRE, WISCONSIN.

HORSE-BOOT.

SPECIFICATION forming part of Letters Patent No. 614,842, dated November 29, 1898.

Application filed February 28, 1898. Serial No. 672,062. (No model.)

To all whom it may concern:

Be it known that I, EDWIN CRALL, a citizen of the United States, residing at Alma Centre, in the county of Jackson and State 5 of Wisconsin, have invented a new and useful Horse-Boot, of which the following is a specification.

The purpose of the present invention is the provision of a protector for preventing injury to the limbs of animals from interfering or other causes resulting in chafing or rubbing the parts opposite the joint by striking them when the animal is speeded or in motion.

The protector is chiefly designed for shielding the fetlock or pastern-joint, and in its construction comprises a band for encircling the leg of the animal contiguous to the joint, a loop applied to the band and projecting from an edge thereof, and a rubber or other flexible ring secured in the projecting end of the loop and having its sides recessed to admit of the sides of the loop coming flush with the ring and the flattened portion of the latter being gripped between the sides of the loop, 25 whereby the said ring is maintained in proper position.

For a full understanding of the merits and advantages of the invention reference is to be had to the accompanying drawings and 30 the following description.

The improvement is susceptible of various changes in the form, proportion, and the minor details of construction without departing from the principle or sacrificing any of 35 the advantages thereof, and to a full disclosure of the invention an adaptation thereof is shown in the accompanying drawings, in which—

Figure 1 is a perspective view of the protector. Fig. 2 is a transverse section thereof. Fig. 3 is a detail view in perspective of the rubber or elastic ring. Fig. 4 is a detail section showing the sides of the loop coming flush with the sides of the ring.

45 Corresponding and like parts are referred to in the following description and indicated in the drawings by the same reference characters.

The band 1 is constructed to have the end 50 portions overlap and be secured by means of a strap 2 and buckle 3, said parts being secured to opposite ends of the band. This

band is composed of two layers of leather or like material, which are stitched together at their longitudinal edges and between which 55 is placed a metal strip 4, sufficiently pliable to be bent, so as to conform to the outline of the leg of the animal to which the device is fitted. This band will be provided in different sizes, thereby enabling animals of varying size to be fitted.

A loop 5 is secured at one end to an edge portion of the band 1 and extends therefrom and supports a ring 6, of rubber or like yielding material. This loop 5 is formed of stout 65 leather, possessing sufficient stiffness to maintain its relation with reference to the band and exert a pressure against the opposite sides of the ring 6, so as to retain the latter in an operative position. This loop is of 70 tapering form and is stitched or otherwise rigidly connected at its inner end with the band 1.

The ring 6, of rubber or like material, is formed with recesses 7 in its sides at the point 75 designed to be fitted between the parts of the projecting ends of the loop 5. These recesses 7 are of a length corresponding to the width of the outer end of the loop 5 and are of a depth corresponding to the thickness of the 80 material from which the loop is formed, whereby when the ring is in position with the loop the sides of the latter will come flush with the sides of the ring, thereby preventing the loop from rubbing and chafing the animal. 85 The provision of the recesses also results in flattening the opposite sides of the ring, and these flattened faces, coming against the inner sides of the loop, serve to hold the ring from turning and in line with the loop, which is essential in order to maintain said ring in a proper position to afford protection to the fetlock or pastern-joint. The outer end portion of the loop 5 is flattened, so as to bring its 90 sides together and cause them to grip and exert a pressure against the flattened faces of the ring provided by the recesses 7, thereby holding the ring and maintaining it in the required position.

The purpose of the band 1 is to secure the 100 protector to the leg or ankle portion of the animal adjacent to the joint to be protected, the parts being arranged so that the ring 6 will overlap the joint or the part thereof to be

protected against injury in the manner set forth.

Having thus described the invention, what is claimed as new, and desired to be secured 5 by Letters Patent, is—

1. In a protector of the character set forth, the combination of a band, a loop secured at one end to the band and having its other end portion projecting beyond an edge thereof, 10 and a ring of rubber or like material supported in the free end of the loop, and having the sides opposite the loop recessed to receive the side portions of the loop and admit of their coming flush with the sides of the ring, 15 substantially as and for the purpose set forth.

2. The herein-described protector comprising a band, composed of layers having secured between them a flexible metal strip and provided at its ends with means for securing 20 the device to the leg of an animal, a loop se-

cured to an edge portion of the band and projecting therefrom and having the sides of the projecting end portion flattened, and a ring of rubber or like material having its sides recessed and flattened and having the reduced 25 part formed by said recesses fitted into the projecting end of the loop, whereby the flattened sides of the ring are gripped between the flattened sides of the loop and the ring held in line with the loop and in proper position when in service, substantially as set forth.

In testimony that I claim the foregoing as my own I have hereto affixed my signature in the presence of two witnesses.

EDWIN CRAIL.
